UNITED STATES PATENT OFFICE.

GEORGE A. LOCKE, OF GLEN COVE, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed March 1, 1924. Serial No. 696,136.

This invention relates to signaling systems and particularly to synchronous telegraph systems.

It is an object of the invention to maintain synchronism of the apparatus associated with the line during a brief interval when no impulses are transmitted over the line. Such an interruption may be due to a temporary opening of the line, to a steady application of potential as occurs in a line swing, or it may occur in the normal operation of a system in which it is desired to change the direction of transmission.

To accomplish this object and in accordance with the features of the invention, means is provided at the respective stations cooperating with the correcting system to maintain approximate synchronism during the interval in which no impulses are transmitted over the line. This and other features of the invention may be more clearly understood by reference to the accompanying drawing which discloses one embodiment of the invention.

Referring to this drawing, the invention is shown in connection with a signaling system provided with means for automatically reversing the direction of transmission over the line. The system per se is not a part of the present invention but is described in detail and claimed in an application of Allison A. Clokey, Serial No. 592,216, filed October 4, 1922.

Each end of the cable is provided with a distributor comprising a sending face S, a receiving face R and a correcting face C, the brush arms A, B and D associated therewith being driven in the well known manner by means of an impulse motor E controlled by a driving fork F. The two distributors at either end of the cable are maintained in synchronism by means of the electrical correction method which is well known in the art comprising an impulse relay G, a corrector relay H and a resistance I which is in series with the driving magnet of fork F. Transmission is accomplished in the usual manner by a perforated tape controlled transmitter K operating in conjunction with the sending face S of the distributor.

The line impulses are received on a line relay M after passing through the amplifier O and are repeated into the printing relay N which operates in conjunction with the receiving face R of the distributor to distribute the received impulses to the proper selecting magnets of the printer P in a manner which is readily understood by those skilled in the art.

The distributor shaft 5 is employed to drive a cam shaft 6 carrying cams 7 and 8 through a train of reduction gears 9 in the manner described in detail in the above mentioned application. The cam 8 is provided with two raised portions 10 and 11 which are adapted to engage cam spring 12 and move it into contact with contact spring 13. In a similar manner, cam 7 is provided with raised portions 14 and 15 adapted to move cam spring 16 into contact with contact spring 17. For equal periods of transmitting and receiving at each station, the raised portions 10 and 11, likewise 14 and 15, are diametrically opposite each other. The cams 7 and 8 are positioned on shaft 6 so that the raised portion of cam 8 engages spring 12 a certain time interval before the raised portion of cam 7 engages spring 16. This time interval is dependent upon the lag of the cable, the lag of the apparatus and the amplifier "shock" and in practice is of the order of four seconds.

Contact spring 13 is connected to segment 18 on sending face S and once in each revolution of brush arm A is connected by the inner brush to common ring 19 which is connected through the winding of polarized relay 20 to ground. In a similar manner, contact spring 17 is connected to segment 21 on receiving face R and is connected by the inner brush of arm B to common ring 22 which in turn is connected to ground through the windings of polarized relay 23. Upon the energization of relay 20 its armature engages contact 25 thereby completing an energizing circuit from battery 26 through the winding of transmitter control relay 27. A resistance 28 is bridged across the winding of relay 27 to make it slow acting. Upon the energization of relay 23 its armature engages contact 29 thereby com-

pleting an energizing circuit from battery 30 to the winding of receiver control relay 31. The line or cable is connected to armature 32 of relay 27 and in the position shown armature 32 is in engagement with contact 33 thus connecting the circuit from common ring 34, outer brush of arm A and segmental ring 35 to the transmitter K. In its alternate position, armature 32 engages contact 36 thus connecting the cable through the amplifier O and the winding of line relay M to ground. Armature 37 of relay 27 is adapted to engage either contact 38 or 39 thus connecting positive or negative battery to spring 12. In its normal position, armature 40 which is grounded is in engagement with contact 41 which is connected to one terminal of correcting resistance I, thus rendering the correcting apparatus inoperative. In its operated position armature 40 engages contact 45 which is joined to contact 47 of relay 31.

Referring to receiver control relay 31, armature 42 is adapted to engage either contact 43 or contact 44 thus connecting either positive or negative battery to spring 16. Armature 46 is connected through the vibrating winding of corrector relay H, common ring 48 of correcting face C which is alternately connected by means of outer brush of arm A and segmental ring 50 to the positive terminal of grounded battery 51 or the negative terminal of grounded battery 52. The resistance elements 54 and 55 are provided to prevent short-circuiting the batteries when the brush bridges adjacent segments. The midpoint of corrector relay H is connected to grounded battery 56 while the outer terminals are connected respectively to the sets of alternate contacts on segmental ring 57 which is connected by means of inner brush of arm D and common ring 58 to the armature of impulse relay G.

In the operation of the system, the station shown is operating as the sending station and impulses are being transmitted to the cable from transmitter K through rings 34 and 35 of sending face S, contact 33 and armature 32 of relay 27. The receiving apparatus is disconnected from the cable at contact 36. Since armature 40 is in engagement with contact 41, the resistance I is grounded at either end thus rendering the correcting apparatus inoperative and making this station the pace setting station. The transmitter K continues to transmit signal impulses until the raised portion of cam 8 moves spring 12 into engagement with spring 13 thus connecting the positive terminal of grounded battery through contact 38, armature 37, springs 12 and 13 to segment 18. As the inner brush of brush arm A engages segment 18, the circuit is extended through common ring 19 and polarized relay 20 to ground. Relay 20 is thus energized and as its armature engages contact 25, the operating circuit for transmitter control relay 27 is completed. As relay 27 is energized, armature 32 moves away from contact 33, thus opening the transmitting circuit, 70 and engages with contact 36 which is connected to the amplifier O and line relay M. At the same time, armature 37 moves from contact 38 to contact 39 thus changing the potential on spring 12. However, by the time this relay is operated, the raised portion 10 has rotated an amount sufficient to open the circuit between springs 12 and 13. As armature 40 moves away from contact 41 and engages contact 45, the short-circuit 80 around resistance I is removed and a circuit is completed from grounded armature 40 through contact 45, contact 47 and armature 46 of relay 31, the vibrating winding of corrector relay H, common ring 48 of correcting face C and then alternately through the segments of segmental ring 50 to positive and negative batteries 51 and 52, respectively. The armature of corrector relay H is thus caused to vibrate in accordance with the 90 movements of brush arm D over segmental ring 50 thus alternately connecting resistance I in and out of circuit with the driving magnet of fork F and thereby maintaining 95 the synchronism at a mean point between the maximum and minimum values. This operation continues for a time sufficient to allow for the lag of the apparatus and cable and the time required to permit the amplifier to function properly at which time the raised 100 portion 14 of cam 7 moves the cam spring 16 into engagement with spring 17. A circuit is thus completed from the positive terminal of a grounded battery through contact 43, armature 42, springs 16 and 17 to segment 105 21 of receiving face R. As the brush arm B rotates, the inner brush completes a circuit from segment 21 to common ring 22 and thence to ground through the winding of polarized relay 23. The operation of this relay closes a circuit from battery 30, through the armature and contact of relay 23 and the winding of receiver control relay 31, causing the operation of the latter. Armature 42 moves from contact 43 to contact 44 thus impressing a negative potential on spring 16. However, by the time this action takes place, springs 16 and 17 are separated and no further action takes place until the raised portion 15 moves into engagement with spring 110 16. As armature 46 moves away from contact 47, the vibrating circuit through corrector relay H is interrupted, thus permitting the normal operation of corrector relay 115 H in conjunction with segmental ring 57 and common ring 58, and causing the station to now operate as the controlled station. Simultaneously, armature 60 of relay 31 moves into engagement with contact 61 thus 120 connecting the armature of printing relay N 125 62 to ground. Relay 20 is thus energized 130

through armature 60, contact 61 to the common ring 62 of receiving face R and thence by the outer brush of arm B to the receiving segments and to the magnets of printer P.

This station now operates as a receiving station until the raised portion 11 of cam 8 has rotated to a point where it engages cam spring 12 and moves it into engagement with 10 spring 13. A circuit is then closed from the negative terminal of grounded battery, through contact 39 and armature 37 of relay 27, springs 12 and 13 to segment 18 of sending face S. Upon the next revolution of 15 brush arm A, a circuit is completed through the inner brush and common ring 19 and the winding of polarized relay 20 to ground. The armature of relay 20 is thus energized and opens the operating circuit of transmitter control relay 27 causing the armatures of 20 this relay to fall back and again assume the position shown in the drawing, thus again connecting the transmitting apparatus to the cable and changing the station to the 25 pace setting station by the short-circuiting of resistance I. A few seconds later the raised portion 15 of cam 7 causes spring 16 to engage spring 17 thus completing an operating circuit for polarized relay 23 from 30 the negative terminal of grounded battery through contact 44, armature 42, springs 16 and 17, segment 21, inner brush and common ring 22 of receiving face R through the winding of relay 23 to ground. The operation 35 of relay 23 causes the opening of the operating circuit for relay 31, allowing its armature to fall back into the position shown thus disconnecting the printing mechanism and permitting the station to again operate 40 as a transmitting station until the raised portion 10 of cam 8 again engages with cam spring 12.

What is claimed is:

1. A signaling system comprising a line 45 over which signaling impulses are transmitted, synchronous apparatus associated therewith, and means effective only upon the cessation of signaling impulses to maintain substantial synchronism during a period in which no impulses of any kind are transmitted over the line.

2. A signaling system comprising a line, 55 synchronous apparatus associated therewith, correcting means responsive to line signals for maintaining said apparatus in synchronism, and further means for supplying correcting impulses during an interval when no impulses of any kind are transmitted over the line.

60 3. A signaling system comprising a line over which signaling impulses are transmitted, synchronous apparatus associated therewith, correcting means responsive to line signals for maintaining synchronism, means 65 for rendering said corrective means inoper-

ative, and additional means effective only upon the cessation of signaling impulses for maintaining substantial synchronism during the period when said first means is rendered inoperative.

70

4. A signaling system comprising a line, synchronous distributors associated therewith, means for reversing the direction of transmission over said line, and means independent of current impulses transmitted 75 over the line for maintaining substantial synchronism during the interval required for said reversal.

5. A signaling system comprising a line, synchronous distributors associated therewith, means for reversing the direction of transmission over said line, and means co-operating with said distributors and independent of current impulses transmitted 80 over the line for maintaining substantial 85 synchronism during the interval required for said reversal.

6. In a signaling system arranged for periodically reversing the direction of transmission, a line interconnecting a plurality of stations, receiving and transmitting apparatus at each of said stations, means at each station for disconnecting the transmitting apparatus from the line, means for subsequently connecting the receiving apparatus 90 to the line, and means independent of current impulses transmitted over the line for maintaining substantial synchronism during the interval intervening between the operation 95 of said first and second means.

7. In a signaling system arranged for periodically reversing the direction of transmission, a line interconnecting a plurality of stations, receiving and transmitting apparatus at each of said stations, means at each 100 station for disconnecting the transmitting apparatus from the line, means for connecting the receiving apparatus to the line a given time interval after the operation of said first means, and means for maintaining 105 substantial synchronism during the interval intervening between the operation of said first and second means.

8. In a signaling system, a line over which 110 signaling impulses are transmitted, means for reversing the direction of transmission over the line, rotary distributors associated with the line, means for maintaining said distributors in synchronism, and additional means effective only during the period of 115 reversal and independent of any impulses transmitted over the line for maintaining the distributors in approximate synchronism during such period.

9. In a signaling system, a line over which 120 signaling impulses are transmitted, synchronous apparatus associated therewith, correcting means responsive to signaling impulses for maintaining synchronism, and means for supplying correcting impulses to 125

130

said correcting means during an interval when no impulses of any kind are transmitted over the line.

10. In a signaling system in which synchronism is normally controlled by the operation of a correcting relay in response to signal impulses transmitted over the line, the method of maintaining synchronism during an interval when no current im-

pulses of any kind are transmitted over the line, which consists in supplying alternate positive and negative impulses to control the operation of the correcting relay during such interval.

In witness whereof, I hereunto subscribe my name this 29th day of February A. D., 1924.

GEORGE A. LOCKE.
